UNITED STATES PATENT OFFICE

2,512,072

FUEL PUMPING UNIT

Charles H. Rystrom, Rockford, Ill.

Application October 25, 1944, Serial No. 560,326

2 Claims. (Cl. 103—42)

1

My invention relates generally to fuel pumping units, particularly those of a type suitable for supplying oil under pressure to oil burners.

Domestic oil burners present somewhat of a service problem, since they are frequently located substantial distances from a factory or shop where they may be serviced, and because it is frequently hazardous to permit the oil burner to remain out of operation for any substantial length of time due to the possibility of freezing water pipes, materials in process, to say nothing of the comfort and health of the inhabitants of the building in which the oil burner is located.

It is thus an object of my invention to provide an improved fuel feed unit for oil burners, which is of extremely simple design and which is constructed of a small number of parts so arranged that they are readily accessible for inspection, service, and adjustment in the field, thus making it unnecessary to return the unit to a factory or service station for repairs.

A further object is to provide an improved fuel unit in which the component parts and subassemblies are so arranged that damage or trouble with one component or subassembly does not necessitate replacement of a major portion of the unit.

Another object is to provide an improved construction in which the part or parts which are the cause of the trouble can be repaired or replaced without disturbing the setting or adjustment of other parts of the unit which are functioning satisfactorily, and in which most of the adjustments and replacements of components or subassemblies may be made without disconnecting any of the piping normally connected to the unit. For example, the fuel oil strainer, the pumping mechanism, or the pressure regulating valve mechanism can be individually removed, cleaned, adjusted, and replaced without disconnecting the unit from the piping or removing the bolts that hold the unit on the burner. Similarly, a new pumping mechanism, together with its shaft, housing, and seal, can be mounted on the valve housing without in most cases requiring the disconnection of any of the piping.

A further object is to provide an improved fuel pumping unit incorporating a pressure regulating and bypass valve of the plunger type, in which both the plunger and its bushing can be quickly removed without disconnecting the unit from the burner, this facility for removal of the regulating valve being of particular advantage

2

when the fuel oil pumped by the unit contains impurities and foreign bodies which tend to cause the valve to stick or fail to seat properly.

A further object is to provide an improved fuel pumping unit having an improved pressure regulating and bypass valve that does not require a press fit of any of the valve parts, and which does not require holding means of the clamp type for positioning them in the housing, such holding and positioning of the pressure regulating and bypass valve being accomplished by a combined valve seat and nozzle port providing element.

A further object is to provide an improved fuel pumping unit particularly adapted for use in conjunction with oil burners, which is extremely simple in construction, reliable in operation, and which may be economically manufactured.

Other objects will appear from the following description, reference being had to the accompanying drawings, in which:

Fig. 1 is an end elevational view of the pumping unit, with the end cap removed;

Fig. 2 is an end elevational view taken in the direction opposite to that of Fig. 1;

Fig. 3 is a fragmentary sectional detail, to an enlarger scale, showing the internal fuel oil high pressure discharge ducts, and taken on the line 3—3 of Fig. 1;

Fig. 4 is a longitudinal sectional view taken on the line 4—4 of Fig. 5;

Fig. 5 is a transverse sectional view taken substantially on the line 5—5 of Fig. 4; and

Fig. 6 is a fragmentary sectional view taken on the line 5—5 of Fig. 4.

In general, the fuel pumping unit comprises a gear pump assembly 10 having a shaft seal assembly 12 detachably secured thereto. The gear pump assembly is detachably secured to a strainer and regulating valve assembly 14, the latter having a pressure regulating valve assembly 16 retained therein by a detachable combined valve seat and outlet port 18.

Referring particularly to the gear pump assembly, it comprises a body 20 having a bore 22 extending longitudinally therethrough. The bore 22 is provided with a pair of keyway slots 24 to permit the ready removal of a drive shaft 26, by providing clearance for the ends of a pin 28 extending diametrically through the drive shaft. This pin provides a separable driving connection between the shaft 26 and a gear 30 which meshes with its counterpart 32 to provide the rotating elements of a substantially conventional gear

3

pump. The gear 32 rotates freely on a stub shaft 34 pressed into the body 20.

As best shown in Fig. 5, the gears 30 and 32 rotate in a suitably conformed opening 36 provided in a casing plate 38. A cover plate 40 and the casing plate 38 are secured to the body 20 by a plurality of cap screws 42. A removable screen 44 is provided with a rim 46 which has a sliding fit around the periphery of the casing plate 38. The cover plate 40 is provided with an oil inlet opening 48, which communicates with the opening 36 at 50, to the left of the gear wheels 30 and 32, shown in Fig. 5. Additional openings of small size may, if desired, be provided to permit flow of oil to the uppermost and lowermost portions of the opening 36 to improve the smooth running characteristics of the pump.

The discharge from the space 52 at the opposite side of the gear wheels flows through a high pressure port 54, the latter communicating by way of a duct 56, formed in the body 20, and a duct 58, formed in a regulating valve body 60, with an annular groove 62 to supply oil under pressure to the regulating valve assembly 16.

The drive shaft 26 is sealed by means of a sealing ring 64 preferably made of bronze or similar alloy, the sealing ring being structurally reinforced by a band 66 of steel or other high tensile strength metal which is pressed over the sealing ring 64. The sealing ring 64 has an annular projection 68 which cooperatively engages with a ring 70, preferably made of Nitrallloy or similar material, which is pressed over a seal ring 72, of steel or similar alloy, clamping a flexible diaphragm 74 between it and a flange 76 formed on the ring 72. The diaphragm 74 may be of any suitable flexible material, such as cloth impregnated with a plastic or similar material, which is oil resistant and makes the cloth sufficiently flexible to permit movement of the ring 72 and cause the ring 70 to maintain sealing engagement with the annular portion 68 of the sealing ring 64 as the latter wears. The ring 72 is pressed to the left by a conical compression coil spring 78, which is seated against a closure cap 82. The cap 82 clamps the peripheral edge of the diaphragm 74 to the end of the body 20, being secured to the body by a plurality of cap screws 84.

The relative rotary movement thus takes place between the bronze annular projection 68 and the ring 70 of Nitrallloy or similar material, thereby providing an oil tight seal. If for any reason this seal needs to be repaired or replaced, it is clear that by removal of the cap screws 84 any component or subassembly of the sealing means may be removed for cleaning, refinishing, or replacement.

Similarly, if any of the components or subassemblies of the gear pump are not operating properly, the gear pump assembly may be removed as a unit by unscrewing cap screws 86 (Fig. 4) by which the body 20 is secured to the regulating valve body 60. In addition, upon removal of an end cap 88, by unscrewing cap screws 90, the strainer 44 may be removed for cleaning or replacement, whereupon the gear pump may be removed after unscrewing cap screws 42.

Within the regulating valve body 60 there is a bore 92 having a counterbore 94 at one end thereof, part of this counterbore forming the annular passageway 62 previously mentioned. A regulating valve sleeve 96 has a chamfered shoulder 98 which has a sliding fit in the counterbore 94 and the chamfer surface of the sleeve presses against a sealing ring 100 which may be made of

4

a suitable semi-soft synthetic rubber, or similar material, which is resistant to the action of oil and will maintain its elasticity for a long time.

The sleeve 96 has a plurality of ports 102 extending diagonally and radially inwardly to provide communication between the annular groove 62 and the bore through the bushing 96. A valve 104 is freely slideable within the sleeve 96 and has its end face recessed to receive a disc 106, preferably made of a synthetic composition rubber, forming a valve face for engagement with a seat 108 constituting part of the valve seat member 110. This valve seat member 110 has a port 112 leading from the valve seat to a tapped outlet opening 114, to which a discharge pipe is adapted to be secured for conveying the fuel oil under pressure to the burner nozzle.

The valve 104 is urged to the right (Fig. 5) by a compression coil spring 116, one end of which 20 has a spring seat 118 frictionally fitted thereto, the spring seat 118 having a conical point 120 fitting in a wider angle conical depression 121 formed in the inner end wall of the valve 104. The other end of the spring 116 abuts against an 25 adjusting nut 122 threaded on a rotatable elongated fillister head stud 124. The stud 124 has a thin nut 126 suitably fixed thereto and is provided with a gasket 128, the kerfed head 130 of the screw 124 being accessible for engagement 30 by a screw driver through an opening 132 formed in a cap 136, the latter being secured to the body 60 by a plurality of cap screws 138.

The nut 122 is held from rotation by a pair of pins 140 pressed in the cap 136 and projecting 35 freely through notches formed in the flanged portion of the nut 122. It will thus be clear that by rotating the adjusting stud 124 the degree of compression of the spring 116 may be varied so as to determine the pressure required to move the valve 40 104 from its seat 108. The valve 104 has an annular groove 144 which under all circumstances is in communication with the passageways 102.

Oil in the annular groove 62 has access to the face of the valve member 106 through a plurality 45 of slots 146 cut in the end face of the sleeve 96. Thus, when the pressure at the outlet of the pump exceeds a predetermined desirable value, the valve 104 will move to the left (Fig. 4) to permit discharge of the oil through the nozzle connected 50 outlet port 112. When the pressure becomes materially greater than the predetermined pressure required for proper discharge of the oil from the burner nozzle, the spring 116 will be further compressed and the annular groove 144 will form a 55 path for the flow of oil from the annular groove 62 through the ports 102 and the annular groove 144 to a plurality of symmetrically arranged ports 148 which are formed in the valve sleeve 96.

The oil which thus enters the bore 92 may be 60 returned to the fuel tank, or other source, through a pipe connected to a tapped outlet opening 150, the oil flowing past a plug 152, through a passageway 153. When desired, the oil discharge into the bore 92 may be returned to a tapped inlet port 154 through a bypass duct 156, by removal 65 of the plug 152 and inserting a solid plug in the tapped outlet 150. The oil from the tank or other source is supplied to the pump through a conduit connected to the inlet port 154, which 70 communicates by way of a passageway 158 with the screen chamber 160.

As best shown in Fig. 6, a tapped suction port 162 is provided, this port being in communication with the duct 158. The latter port is provided 75 for the attachment of a vacuum gauge when

it is desired to check the operation of the pump. At other times this port is closed by a pipe plug. Another port 164 (Fig. 6) is provided for attachment of a pressure gauge, this port communicating via a duct 166 with the annular groove 62, the gauge thus being enabled to indicate the pressure generated by the gear pump, and assuming that oil is being discharged at the burner nozzle, it will also indicate approximately the pressure at which the oil is being discharged from the port 112 to the nozzle, making due allowance for the pressure drop in the piping leading to the nozzle.

From the foregoing it will be clear that should the regulating valve operate improperly for any reason whatsoever, the serviceman need merely remove the cap 110, whereupon the valve body 104 and all parts carried thereby, as well as the sleeve 96, may readily be removed, since these parts have sliding fits relative to one another and the sleeve 96 has a sliding fit in the body 60. Upon replacement of the sleeve 96 and valve 104, the sleeve is tightly sealed by means of the composition rubber ring 100, when the cap 110 is secured in place by means of its cap screws 111. Suitable gaskets (not shown) may be used wherever necessary to assure oil tight seals between the various separable parts.

It will also be understood, from the foregoing description, that the shaft seal may readily be removed and replaced without disturbing the gear pump mechanism or the regulating valve mechanism. Similarly, the gear pump may readily be removed with the shaft seal without disturbing the regulating valve or the shaft seal. For servicing the gear pump, the cap 88 and strainer 44 may be removed, thereby making cap screws 42 accessible and permitting removal of the gear pump. Adjustment of the pressures at which the valve 104 opens to permit discharge of oil to the burner nozzle and the pressure at which the bypass begins to take place are adjustable without removing any parts of the unit. If the gasket 128 for the adjusting screw 124 should leak, or if the valve 104, or any part carried thereby should need repair or replacement, the cap 136 may be removed, making all of these parts accessible for removal. When it is necessary to clean the sleeve 96 or to remove it for any other purpose, the cap screws 111 are removed, whereupon the cap 110 which constitutes the outlet and valve seat, may be pushed to one side, with the pipe still connected to it, and the sleeve 96, together with the valve body 104 and parts associated therewith, may be removed. When it is desired to clean the screen 44, it is necessary merely to remove the cap 88.

It will thus appear that each movable component of the unit is readily accessible without in any way disturbing other components, and without making it necessary to disconnect the unit from any of the pipes or from the burner. The regulating valve may be utilized as a pressure responsive bypass from the high pressure side of the pump to the low pressure side thereof through the duct 156, or the oil which escapes past the pressure regulating valve may flow through the outlet 150 and pipe connected thereto to the source of oil.

Due to the provision of several radial ports 102 and 148, which are preferably, but not necessarily, equally spaced circumferentially of the valve sleeve 96, it has been found that the valve member 104 will not vibrate but instead will move smoothly and gradually to the position re-

quired for the maintenance of the proper operating pressure. Thus pulsations in the oil flowing to the burner nozzle are avoided. If such pulsations in the pressure fuel supplied to the burner nozzle were present, they would cause unsatisfactory operation of the burner.

The unit is thus of extreme simplicity and ready accessibility of its components. This ready accessibility of the parts of the unit is also a factor contributing to low cost of manufacture of the unit because of the rapidity with which the various parts may be assembled.

While I have shown and described particular embodiments of my invention, it will be apparent that numerous variations and modifications thereof may be made without departing from the underlying principles of the invention. I therefore desire, by the following claims, to include within the scope of my invention all such variations and modifications by which substantially the results of my invention may be obtained through the use of substantially the same or equivalent means.

I claim:

1. A pressure regulating device for the fuel supply system of an oil burner comprising a body having a main bore, a counterbore coaxial with the main bore and providing a shoulder at the junction of the two bores, a freely removable sleeve having a flange engaging the shoulder, the flange having a free sliding fit in the counterbore and the remaining portion of the sleeve having a free sliding fit in the main bore, said sleeve having a vent port in the wall thereof, a gasket between the shoulder and the flange, a seat forming a discharge port through which fuel is discharged to the oil burner, a piston valve having a close sliding fit in said sleeve and having a relatively wide annular groove spaced from its ends, means on the closed end of the piston valve to engage the seat at the discharge port, the major portion of the area of the closed end of the piston being subjected to the pressure of fuel supplied to the device when the piston is in position engaging the seat and the entire cross sectional area of the piston being subjected to the pressure of the fuel supplied when the piston is moved away from the seat, a spring compressed to hold the piston in engagement with the seat as long as the pressure of fuel supplied is less than a predetermined value, a port in the sleeve to conduct fuel supplied to the annular groove in the piston valve, the vent port in the sleeve being located so as to communicate with the annular groove in the piston valve only when the latter has been moved by the pressure of the fuel a predetermined distance from the seat, and a removable closure secured to the body to hold the sleeve in position, said closure and body having flat engaging surfaces whereby said closure may be slid laterally for removal, the removal of the closure making the sleeve, valve, gasket, and spring accessible for removal without disconnection of any pipes.

2. A pressure regulating valve comprising a body having a bore and having a portion of enlarged diameter at one end of the bore to provide a shoulder, a ported sleeve having a sliding fit in the bore and having a flange engageable with the shoulder, a gasket forming a seal between the flange and the shoulder, means for connecting the source of fuel under pressure to one end of the bore, a cylindrical valve member slidable in the sleeve and normally having its end

face subjected to the pressure of the fuel supplied, said valve member having a groove co-operable with the ports in the sleeve, one port in the sleeve affording a bypass for the fuel when the pressure thereof exceeds a predetermined maximum value, means providing a valve seat with a discharge port, adjustable resilient means engaging the valve member and forcing it against said seat, and a single removable member holding the sleeve valve member and resilient means in assembled relationship within the body, said removable member and body having flat engaging surfaces whereby said member may be slid sideways for removal, said valve seat being movable with said member, the removal of the removable member making the sleeve, valve member, and resilient means readily accessible for removal without disconnection of any pipes.
